BREECH ACTUATING AND CONTROL
SYSTEM

Harry F. Vickers, Detroit, Mich., assignor, by
mesne assignments, to Vickers, Incorporated,
Detroit, Mich., a corporation of Michigan

Application December 12, 1935, Serial No. 54,026

9 Claims. (Cl. 89—4)

1

This invention relates to a breech actuating and control system and has to do particularly with a novel control and actuating circuit for the breech mechanism of a gun mount.

The present invention contemplates the provision and connecting up of hydraulic actuating and control mechanism for moving the breech mechanism to and from firing position and for ejecting the cartridge case, in combination with means actuated by the recoil of the gun for supplying motive power to said actuating and control mechanism.

Another feature of the invention has to do with a compound hook-up and control circuit, including a breech mechanism actuating and control circuit, an accumulator circuit controlled by the recoil of the gun, and a return or tank circuit, whereby motive power is normally supplied through a compact circuit and accumulating means by the recoil of the gun, and which motive power may, in an emergency, be supplied from either one of two sources. Other features of this compound hook-up, resulting in a compact actuating and control circuit with a main positive and auxiliary sources of pressure supply, will be more clearly brought out in the specification and claims.

The accompanying drawing is a diagrammatic view of a breech actuating and control mechanism embodying the present invention and showing in particular the compound circuit hook-up including a plurality of means for furnishing fluid pressure.

It will be understood that the present invention relates generally to the storing up of power incident to the recoil of a gun, and the manner of storing up of such power and applying the same to actuate and control the breech loading and unloading mechanism; the hydraulic actuating and controlling means utilized in this system may be of any standard design and for this reason are shown diagrammatically.

In the embodiment shown in the drawing, the rear end of the gun mount or breech is generally designated 2, the ejector unit for the cartridge 3 being diagrammatically shown as at 4 and the breech block as at 5. A chain type rammer unit for moving the charge into position is shown in dotted lines and is generally designated 6; this rammer unit would normally be positioned closely adjacent the breech of the gun so that the rammer unit 7 as shown in solid lines would be positioned adjacent the breech of the gun; the rammer unit is shown positioned away from the breech to make the diagrammatic illustration

2

clearer, and because the rammer unit per se forms no part of the present invention.

An oil reservoir is diagrammatically shown as at 8 and is connected through a check valve 9 and a conduit 10 to a charging cylinder 11; this charging cylinder in turn is connected through an extension of the conduit 10, a check valve 12, and conduit 13, with an accumulator 14. A piston 15 forming a part of the charging cylinder 11 is pivotally connected to the gun mount as at 16, whereby recoil of the gun will force any liquid in the cylinder 11 through the conduit 10, check valve 12 and into the accumulator 14, and a return movement of the piston 15 will draw up oil from the reservoir 8 past the check valve 9 and into the cylinder 11. Any leakage past the piston 11 is returned through the conduit 17 to the reservoir 8.

A conventional pilot control valve is shown as at 18 and connects the pressure conduit 19 with one or the other of two conduits 20 and 21. The conduit 20 is connected to the upper end of a breech block cylinder 22 and by means of branch conduit 23 is also connected to an extractor operating valve 24 and through a check valve 25 and conduit 26 to one end of an ejector cylinder 27. The other end of the ejector cylinder 27 is connected through a conduit 28 with the conduit 21 and also by means of auxiliary conduits with the operating valve 24 and to the bottom end of cylinder 22. In the position of the control valve 18, as shown in the drawing, the conduits 20 and 21 are connected through a return conduit 29 with the reservoir 8.

Power required for initially building up pressure in the accumulator 14 may be supplied from electric motor 30 and pump 31 circulating liquid from tank 32, which tank for the purpose of clarity only is shown separate from tank 8.

This motor and pump unit need only be of such small size as to take care of the charging of accumulator 14 and the emergency requirements for the rammer unit 6, and thus may be reduced in size and power to a minimum. In place of time and pressure controls I have shown a single connection between the pump 31 and accumulator 14 as by means of a conduit 34, throttle valve 35 and check valve 36. An emergency connection is made between the reservoir 8 and accumulator 14 by means of a hand operated pump 37, through conduit 38, conduit 39 and check valves 40 and 41.

In operation, with the parts in the position as shown in the drawing, the firing pin in the breech block 5 may be fired in the usual manner

and the charge exploded. Before firing of the gun, the throttle valve 35 or equivalent means, may be set to supply a small pressure to the accumulator 14, or the valve may be manually opened from a closed position to supply charging pressure to the accumulator 14. Firing of the gun and reciprocation of the piston 15 due to the recoil of the gun will charge the cylinder 11 with a supply of oil from the reservoir 8 which reservoir would normally be a part of tank 32. To lower the breech block 5, the control valve 18 is moved to open position, or down, as viewed in the drawing, admitting pressure from the accumulator 14, through conduit 19 and into conduit 20, to the upper end of the breech block operating cylinder 22, moving the breech block down. At the end of its downward stroke, the breech block contacts with the member 24a of the extractor valve 24, and moves the valve against the action of a spring 42, whereby to connect the pressure line 23 with the conduit 26 and the operating end of the ejector cylinder 27. Movement of the piston within the ejector cylinder 27 causes the empty cartridge 3 to be ejected.

Return of the lever 43 and valve 18 to neutral position, or the position shown in the drawing, opens both lines 20 and 21 to the reservoir 8. This action automatically vents both ends of the operating cylinder 22 and allows a buffer spring member 44 to raise the piston 45; this movement raises the breech block 5 sufficiently to first free the member 24a and then allow the valve member of valve 24 to return to normal inoperative position, as shown in the drawing. The movement of the valve 18 to neutral position also vents both ends of the extractor cylinder 27, and the piston in cylinder 27 is returned to the position shown in the drawing by means of a spring 46, the oil in the actuating end of the cylinder 27 returning through check valve 25 to the tank and to the rod end of cylinder 27.

After the ramming of another projectile and cartridge into the gun, the breech block 5 will be raised to firing position by raising the lever 43 and admitting the pressure through the conduit 21 to the lower end of the cylinder 22. When the breech block is fully raised, it may be locked in position by the usual bolt means (not shown); afterwards the control valve 18 may be moved to neutral position, again venting both ends of the breech block operating cylinder 22.

An important feature of the present invention is the fact that with each recoil of the gun 2, the piston 15 will recharge the accumulator 14 and thus during any continued firing action the main source of power will be furnished by the accumulator 14 to continuously actuate the breech block, ejector and rammer mechanism. While, of course, the recharging cylinder 11 and the other elements of the operating and control system are kept to a minimum size and weight, it will be seen that the cylinder 11 can have most any capacity desired, corresponding to the capacity of the accumulator 14 and the effective size of the cylinders 22 and 27, and the motor and control unit 33.

Fluid pressure for operating the rammer motor and control unit 33 is supplied from the accumulator 14 through the conduit 19 and the auxiliary conduit 19a. Throttle valves 48 and 49 may be inserted in the system as shown to control the maximum flow of actuating liquid to the motor 33 and to the cylinders 22 and 27. A relief valve 50 is preferably inserted between the conduit 10 and the return line, and the spring of said relief

valve is so set as to open the conduit 10 to the tank when the liquid in the accumulator 14 reaches a predetermined pressure.

In the event of the failure of the recharging cylinder 11, it will be seen that if the throttle valve 35 is partially open, after the initial charging step, the pump 31 will supply a limited amount of pressure to the accumulator 14, and in any event this pressure supplied by the pump 31 will supply sufficient pressure to actuate the motor and control unit 33 to cause actuation of the rammer unit 6. It will also be obvious that the throttle 35 may be moved to wide open position to supply pressure equal to the full capacity of the pump 31 so that all the parts of the entire system may be operated at a speed equal to the combined capacity of the accumulator 14 and the pump 31. It will also be apparent that the entire capacity of the pump 31 may be utilized in actuating the rammer 6, by closing the throttles 35 and 49; and in which event, the hand pump 37 can be utilized for supplying fluid pressure to the cylinders 22 and 27. In the event of failure of both the cylinder 11 and the pump 31, pressure may be supplied to the accumulator by the hand operated pump 37, in which event the pressure supplied to the accumulator by the pump 37 could be used in operating the units of the entire system, or used in operating the rammer unit or the breech block and ejector units as desired.

It will thus be seen by this simple, compound system that complete hydraulic actuating and control may be obtained with actuating and control units reduced in weight and size to a minimum, that the charging of the rammer, breech block and ejector actuating-control system is normally automatic in that the main source of power is supplied by the recoil of the gun, and that the entire system is practically breakdown proof by the compounding of the three circuits.

What I claim is:

1. A gun breech actuating and control system comprising a hydraulic motor for actuating a rammer, hydraulic motors for respectively actuating a breech block and ejector, a hydraulic pressure accumulator connected to, and adapted to accumulate liquid under pressure for actuating said motors, a pump to be actuated by the recoil of the gun for charging the accumulator with liquid under pressure, a manually operated control valve interposed in hydraulic connection between said accumulator and breech block and ejector motors and adapted to direct liquid under pressure to said motors, and a control valve operated by the movement of said breech block to direct pressure to said ejector motor to cause the ejecting movement of said ejector.

2. In a gun having a breech and breech block and rammer, a gun breech actuating and control system comprising a hydraulic motor for actuating said rammer, an ejector including an automatic spring return therefor, hydraulic motors for respectively actuating a breech block and said ejector, said hydraulic pressure accumulator connected to, and adapted to accumulate liquid under pressure for actuating said motors, a manually operated control valve interposed in hydraulic connection between said accumulator and breech block and ejector motors and adapted to direct liquid under pressure to said motors, a control valve operated by the movement of the breech block after it reaches the end of its normal stroke to direct pressure to said ejector motor to cause the actuation of the ejector only when said breech block is away from the breech, and means

to return said last named valve to normal position to allow said ejector to return to initial ejecting position while the breech block is still at the end of its normal stroke.

3. In a gun having a breech and breech block and rammer, a gun breech actuating and control system comprising a hydraulic motor for actuating said rammer, an ejector, hydraulic motors for respectively actuating said breech block and said ejector, a hydraulic pressure accumulator connected to, and adapted to accumulate liquid under pressure for actuating said motors, a manually operated control valve interposed in hydraulic connection between said accumulator and breech block and ejector motors and adapted to direct liquid under pressure to said motors, a control valve operated by the movement of the breech block away from the breech and after it has reached the end of its normal stroke to direct pressure to said ejector motor to cause the actuation of the ejector only when said breech block is away from the breech, and a power driven pump connected both to said motors and accumulator for initially charging the accumulator and actuating the motors in the event of failure of said accumulator.

4. A gun breech actuating and control system comprising a breech block and ejector and hydraulic motors for actuating same, a source of fluid pressure, valve means for controlling the flow of fluid pressure to said breech block motor for lowering the breech block, a control valve for said ejector motor actuated by the movement of the breech block away from the breech and after it has reached the end of its normal stroke to direct fluid pressure to said ejector motor, and means responsive to the relief of pressure in the breech motor for automatically returning said last named valve to a position such as to relieve the pressure in the ejector motor and permit return of the ejector to initial position while the breech block is still away from the breech.

5. In a gun having a breech and breech block and rammer, a gun breech actuating and control system comprising a hydraulic motor for actuating said rammer, an ejector, hydraulic motors for respectively actuating said breech block and said ejector, a hydraulic pressure accumulator connected to, and adapted to accumulate liquid under pressure for actuating said motors, a manually operated control valve interposed in hydraulic connection between said accumulator and breech block and ejector motors and adapted to direct liquid under pressure to said motors, a control valve operated by the movement of the breech and after it has reached the end of its normal stroke block away from the breech to direct pressure to said ejector motor to cause the actuation of the ejector only when said breech block is away from the breech, and a plurality of power charging devices for said accumulator including a power driven pump connected both to said motors and accumulator for initially charging the accumulator and actuating the motors in the event of failure of said accumulator.

6. A gun breech actuating and control system comprising hydraulically operated motors for actuating a rammer, breech block and ejector, a hydraulic circuit for said system including control valves and an accumulator, an oil reservoir, and a recharging piston and cylinder structure having one portion connected to the gun and another portion movable relative thereto, con-

duits leading from said cylinder to said oil reservoir and accumulator, check valves in said conduits, the piston and cylinder and check valve arrangement being such that the actuation of said recharging piston and cylinder by the retraction of the gun fills the cylinder and the recoil of the gun furnishes fluid under pressure to said accumulator, one of said control valves being interposed between said accumulator and said hydraulic motors for directing liquid under pressure thereto, and another control valve operated by the movement of said breech block to direct pressure to said ejector motor to cause the ejecting movement of said ejector.

15 7. A gun breech actuating and control system comprising hydraulic piston and cylinder structure for actuating the breech block and ejector, a hydraulic circuit for controlling and actuating said piston and cylinder structure including control valves and an accumulator, an oil reservoir, and a recharging piston and cylinder structure connected to the gun and to said oil reservoir and accumulator, said connections being such that the recharging cylinder structure is filled by the retraction of the gun, a rammer circuit including a pump, a conduit connecting said pump to said accumulator whereby the accumulator may be charged by the recharging piston and cylinder or by the pump, or both, and means positioned between the accumulator and said piston and cylinder structure for controlling the maximum flow of actuating liquid thereto.

20 8. A gun breech actuating and control system comprising a breech block and ejector and hydraulic motors for actuating same, a source of fluid pressure, valve means for controlling the flow of fluid pressure to said breech block motor for moving the same away from the breech, a control valve for said ejector motor so positioned 30 as to be actuated by the breech block after it has reached the end of its normal stroke, and means responsive to the relief of pressure in the breech motor for moving the breech motor piston a short distance and sufficient to release said last named valve and permit return of said valve to its normal position.

25 9. A gun breech actuating and control system comprising hydraulic motors for actuating a rammer, breech block and ejector, a hydraulic circuit for said system including control valves and an accumulator, an oil reservoir, and a recharging piston and cylinder structure connected to the gun and to said oil reservoir and accumulator, the actuation of said recharging piston and cylinder by the retraction of the gun filling the cylinder and by the recoil of the gun furnishing the main source of fluid under pressure to said accumulator, said hydraulic circuit including a rammer circuit having a relatively small 35 pump, said rammer circuit being connected to said accumulator through a valve for charging said accumulator and supplying pressure thereto in an emergency, a hand operated pump connected to said accumulator for charging said 40 accumulator and supplying pressure thereto in an emergency, one of said control valves being interposed between said accumulator and said hydraulic motors for directing liquid under pressure thereto, and another control valve operated 45 by the movement of said breech block to direct pressure to said ejector motor to cause the ejecting movement of said ejector.

HARRY F. VICKERS.
